Primary Examiner — Martie K Holtje*(74) Attorney, Agent, or Firm* — Gowling Lafleur Henderson LLP; Joseph Conneely(57) **CLAIM**

The ornamental design for an unmanned aerial vehicle, as shown and described.

DESCRIPTION

FIG. 1 is a front perspective view of an unmanned aerial vehicle according to the design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions shown in broken lines in FIGS. 3 and 7 do not form part of the claimed design.
